United States Patent Office

Des. 233,758

Patented Nov. 26, 1974

233,758

COMPUTER MAINFRAME CONSOLE

Seymour R. Cray, Lester T. Davis, and Maurice D. Roush, Chippewa Falls, Wis., assignors to Control Data Corporation, Minneapolis, Minn.

Filed Mar. 15, 1973, Ser. No. 341,429

Term of patent 14 years

Int. Cl. D14—02

U.S. Cl. D26—5 C

Fig. 1

FIG. 3

FIG. 1 is a perspective view of a computer mainframe console, showing our new design;

FIG. 2 is a front elevational view thereof; and

FIG. 3 is a top plan view thereof.

The sides and rear of the computer mainframe console have the same appearance as the frontal view.

We claim:

The ornamental design for a computer mainframe console, as shown and described.
